EX

OR D 18,906

Feb 5, 1889

UNITED STATES PATENT OFFICE.

WILLIAM T. SMITH, OF PHILADELPHIA, PENNSYLVANIA.

DESIGN FOR A RUG.

SPECIFICATION forming part of Design No. 18,906, dated February 5, 1889.

Application filed January 11, 1889. Serial No. 296,109. Term of patent 3½ years.

To all whom it may concern:

Be it known that I, WILLIAM T. SMITH, a citizen of the United States, residing at Philadelphia, in the county of Philadelphia and State of Pennsylvania, have invented and produced a new and original Design for a Rug, of which the following is a specification, reference being had to the accompanying photographic print, forming a part thereof, which conveys to any one skilled in the art of rug-weaving a clear understanding of the same, and is sufficient to enable such person to use my invention.

The photographic print shows but one of the end borders. The end border not shown is the repeat of that which is shown.

What I claim as my invention, and desire to secure by Letters Patent, is—

The design for a rug, consisting in the ornamentalations shown in the photographic print accompanying this specification.

WILLIAM T. SMITH.
